UNITED STATES PATENT OFFICE.

JACOB PLEIN, OF PLAINVIEW, MINNESOTA.

LOADING DEVICE.

1,391,852.

Specification of Letters Patent. Patented Sept. 27, 1921.

Application filed October 22, 1920. Serial No. 418,859.

To all whom it may concern:

Be it known that I, JACOB PLEIN, a citizen of the United States, residing at Plainview, in the county of Wabasha and State of Minnesota, have invented certain new and useful Improvements in Loading Devices; and I do hereby declare the following to be a full, clear, and exact description of the invention, such as will enable others skilled in the art 10 to which it appertains to make and use the same.

This invention relates to a loading device and is illustrated in a device which is of particular utility upon a farm.

15 It is an object of the invention to produce a simple and efficient loading device which can be readily and easily moved from place to place and which is of great adaptability.

Another object of the invention is to provide such device which may be readily taken down and disassembled and which, when so disassembled, can be stored in a comparatively small space.

These and other objects of the invention 25 will become apparent as the description proceeds in connection with the accompanying drawings in which like reference characters are used to designate the same parts throughout the various views, and in 30 which—

Figure 1 is a diagrammatic view showing the device and one method of using the same;

Fig. 2 is a central longitudinal section of the boom device proper;

35 Fig. 3 is a perspective view of the loading fork constituting a part of the device; and

Figs. 4 and 5 are details of portions of the boom and the sheaves carried thereby.

Referring to the drawings, the loading device 40 comprises a portable structure A, the load carrier B, and the operating cable C.

The device A comprises a platform 1 of any suitable construction which is supported upon wheeled trucks 2. This platform may 45 be provided at each end with any suitable type of bracing member shown as 3 in Fig. 1, which will be used to securely set or anchor the device in any desired position. Located centrally transversely of and at an in-

50 termediate part longitudinally of the platform 1 is a post member 4 which is pivotally mounted to the platform at its lower end by a pivot 5, and which is adapted to swing in a plane disposed longitudinally of the

55 device. When erected to vertical position, as shown in Figs. 1 and 2, the post is securely

braced by rods 6, 7 and 8. The rods 6 extend from each side of the post to each corner of the platform most nearly adjacent the post. The rods 7 extend from each side of the post to positions at the side of the platform approximately the same distance from the center of the post as are the corners to which the members 6 extend. The members 8 extend from the side of the post to points 60 on the platform at each side of the post and at equal distances from the base thereof. The supporting members 6, 7 and 8 are preferably connected to the post by having loops formed at their ends adapted to embrace a 70 bolt 9 which passes through the post and is suitably secured therein. At their lower ends, the members are preferably formed as hooks which are adapted to engage suitable eye-bolts 10 which are secured in the platform 1. While eight of these bracing members have been shown, it will be understood that any desired number may be used which may, if preferred, be connected at different 75 vertical positions along the sides of said post. 80

At the top thereof, the post 4 is arranged to support a boom member 11. This boom member, as shown, comprises two spaced longitudinal members 12 connected at their ends by members 13, these members being 85 secured together in any suitable manner. At an intermediate point, somewhat nearer one end than the other, the boom has bolted thereto an upper member 14 and lower heavier member 15. Passing through these 90 members and designed to be seated in a central socket in the post 4 is a pivot member 16, by means of which the boom member 11 is mounted for swinging movement in a horizontal plane. The boom member 11 is arranged to project out over the end of platform 1 nearest which the post 4 is located. Between this end of the boom and the post 4 is located a sliding sheave structure 17. This structure comprises two blocks 18 arranged to slide upon members 12. Supported at each end of the blocks 18 and suitably secured thereto by screws or bolts 19 are Y-shaped brackets 20 having their central portion depending between the members 12 and formed with a bearing 21 at their lower ends. A rod 22 is mounted in these bearings and projects from one of them at the side adjacent the end of the boom. The sheave housing 23 is mounted on the rod 100 22 for swinging movement thereon and has journaled between its depending side 24 a

sheave 26. The projecting end of rod 22 has an eye or loop 27 formed thereon. An eye-bolt 28 is secured in the end piece 13 of the boom between the members 12.

5 A sheave or pulley 29 is mounted in alignment with the space between members 12 between the post 4 and the other end of the boom. This pulley is carried in suitable brackets 30 mounted on the underside of member 12. This end of the boom projects above the platform 4, and a depending sheave structure is also mounted at this end. This structure comprises a pair of blocks 31 mounted on top of the members 12 and 13 10 at the end of the boom and having mounted thereon, brackets 32 which are secured thereto by screws or bolts 33. These brackets 32 form bearings for a member 34 formed of rod-like material which passes 15 therethrough and has its sides 35 bent downward at each side of the boom and formed at some distance below the same into a double loop 36. Depending between the members 12 and mounted at its upper end 20 for swinging movement on the member 34 is a sheave carrying bracket 37 in which a sheave 38 is mounted for rotation. A rod 39 having a hook 40 at its upper end arranged to hook into the loop 36, extends 25 vertically downward and has a hook 41 at its lower end adapted to hook into an eye-bolt 42 pivotally mounted near the center of the platform. A sheave 43 is mounted for rotation in a swinging bracket 44 which is 30 pivotally mounted near the eye-bolt 42. Bracing rods 12^a are secured in members 13 and extend longitudinally of members 12 and along the sides of block 13.

The loading member B is illustrated in 35 Fig. 3. This device comprises a handle or controlling member 45 having a grip 46 formed on one end thereof. The other end of this handle is formed with an aperture which constitutes a bearing for an oscillating 40 rod or member 47. This member extends transversely of the handle and, at its outer ends, is journaled in brackets 49 which are bent to converge and be secured to the handle 45 by bolts or rivets 46. The ends 45 of member 47 project beyond the bracket 49 and have journaled thereon the ends of a bent bail 50 which is formed with a loop 51 at its upper central portion and in which loop a sheave housing 52 is mounted for 50 swiveling movement. A forked structure comprising side members 53 and intermediate prongs or members 54 rests upon and is rigidly secured to the pivoted or oscillating member 47. A strap member 55 extends under the fork and the prongs 53 and 54 are each rigidly secured thereto by staples 56 or by any other suitable means. The ends of the strap member 55 project upwardly at each side of the fork, as shown 60 at 57, and a flat frame member 58 of general

U-shape form has its side members bolted or riveted to the ends of these members 57. The ends of member 58 are curved downwardly and secured to the side members 53 of the fork. While, as illustrated, these 70 ends are welded or integrally secured to the members 53, it will, of course, be understood that they may be secured thereto by screws, rivets, or any other suitable means. Vertical members 59 equally spaced at each 75 side of the member 45, are rigidly secured to the rear of frame member 58 and the rear portion of the prongs of a fork. Nuts 60 are screwed onto the end of member 47 to retain the bail 50 in place.

Projecting from the top of the fork rearwardly and centrally thereof is a member 61 which is adapted to project into and be engaged by a yoke member 62 which is pivoted to the sides of member 45. A lug 63 projects above the yoke member 62 centrally thereof and rod 64 connects this lug with the intermediate part of a handle lever 65 which is also pivoted to the sides of member 45. A spring 66 holds the yoke member 62 normally in a position to engage the projection 61. A sheave 67 is journaled for rotation on a pivot secured to the underside of member 45 adjacent the ends of members 48.

The projection 61 constitutes a tripping tongue. When the fork is being used to carry material, it occupies the position shown in full lines in Fig. 3. In this position, the spring 66 holds the yoke 62 in 100 position to engage the tripping tongue 61. When it is desired to trip the fork to discharge the load thereon, the handle lever 65 is pulled rearwardly. This swings the yoke 62 against the tension of spring 66 and disengages it from tongue 61. The weight of the fork then swings it to the position shown in dotted lines in Fig. 3.

The method of using the loading device is illustrated in Fig. 1. The cable C is arranged with one end stationarily secured in loop 27. This cable is then passed through the sheave 52 of the loading device, then over sheave 26 back between members 12, over sheave 29, then over sheave 38 and 115 downwardly around sheave 42. At an intermediate point in the cable, beyond the sheave 43, the power means is disposed. In Fig. 1 this is shown as a tractor D. It will, of course, be understood that a horse or any 120 other traction means may be used. From the power means the cable is passed over a sheave or pulley 68 which is secured to a stake, or other suitable fixed stationary member 69. From the sheave 69 the cable 125 is led over a sheave or pulley 70 which is also carried by some suitable fixed member 71. From the pulley 70, the cable passes to the loading device and is arranged to run upon sheave 67 thereon, and from this 130

point, the cable passes to a fixed stake or member 72 and has its end fixed thereto in a stationary position. The movable pulley structure 17 will be anchored in a desired 5 position to the eye-bolt 28 in the end of the boom by a section of cable 73. A wagon shown in Fig. 1 as E, or any other means which it is desired to load, will be placed in position under the projecting end of the 10 boom.

The braces 3 comprising sharpened iron bars will hold the device A in proper position.

The power means will now be moved in 15 the direction of the arrow *a* in Fig. 1. This will slacken the cable connected to the bail 50 of the load carrier B and the said carrier will be pulled backwardly by the portion of the cable passing over the sheaves 68 and 20 70. A load carrying device can now be brought into the desired position with respect to the hay, manure, stones, or other material which it is desired to load. When 25 said member is suitably disposed, the same will be held and guided by means of the handle 45. The power means is now moved in the direction of arrow *b*, Fig. 1, and the load carrying member B will be drawn along the ground until it arrives at a position 30 substantially under the boom, when it will be elevated by the cable running over sheave 26 and be swung into position over the wagon E. When in proper position, the fork will be tripped to discharge the material 35 carried thereon into the wagon E. The direction of movement of the power means will then be reversed and the operation repeated. It will be noted that the member 26 is capable of lateral swinging 40 movement and that the boom member can also swing laterally to a considerable extent. The swinging movement of the beam is limited by its connection with the platform through member 39.

45 When it is desired to take down the device, the bracing members 6, 7 and 8 will be unhooked from the eye-bolts at their lower end, and the member 39 will be, likewise, unhooked from the member 42. The post 4 can now be swung downwardly upon the platform 1 and the boom 11 removed therefrom by lifting the pin 16 from its socket. All 50 of the parts can now be laid upon the platform 1 and will occupy a comparatively 55 small space. As the platform 1 is supported upon trucks, the device can readily be moved to any place where it is to be used.

It will thus be seen that applicant has 60 provided a simple and efficient loading device capable of a wide range of utility. The device can be quickly taken down and transported from place to place and can be just as quickly set up for use.

It will, of course, be understood that the 65 fixed members 69, 71 and 72 can be disposed

in other positions than that shown, and such positions will be determined by the requirements of the particular use to which the device is being put.

It may also be desirable to have a number 70 of different types of load carrying members on hand which are adapted for the different materials which it is desired to handle, any one of which members can be used with the device at the option of the operator.

75

Generally stated, the invention consists in the matter shown and described, and particularly set forth in the appended claims.

What is claimed is:

1. A loading device having in combination a structure comprising an elevated boom which projects therefrom, a series of sheaves carried by the boom and a sheave carried by the structure below said boom, a cable having one end secured in a stationary position in said boom, a load carrying member having a sheave thereon over which said cable is passed, said cable then passing over the series of sheaves on the boom, the sheave on the structure and being secured to a power 80 means, the other end of the cable being secured in a stationary position at some distance from said structure, a second sheave on said load carrying member over which said cable is then passed, and a plurality of 85 sheaves secured to fixed points also distant from said structure over which the cable passes to the power means. 90

2. A loading device having in combination a portable platform having an elevated 100 substantially horizontal boom projecting over one end thereof, said boom being mounted for limited swinging movement in a horizontal plane, a series of sheaves on said boom, a sheave on said platform, a load carrying member having a supporting sheave at the top thereof and a retracting sheave at the bottom thereof, and a cable, one end of which is secured in a stationary

position to the projecting end of said boom, then passed over the carrying sheave of said load carrying member, thence over the series of sheaves on the boom, the sheave on the platform, and being secured to a power means, the other end of the cable being secured to a stationary member at some distance from the platform, then passed over the retracting sheave of the load carrying member, and two sheaves secured to spaced 110 stationary means over which the cable then passes to the power means, whereby, by reversed movements of the power means the load carrying member will be conveyed to and from the boom. 115

3. A loading device having in combination a horizontal platform member, a pair of wheel trucks upon which said member is mounted, a vertical post mounted near one end of said platform for swinging movement thereon, means for holding said post 120

125

130

in vertical position and a horizontal boom mounted on top of said post for lateral swinging movement, a slideable sheave structure mounted on said boom, means for securing said structure in various positions on said boom, and a plurality of substantially stationary sheaves mounted on said boom.

4. A collapsible loading device having in combination a horizontal platform, a vertical post on said platform pivoted thereto at its lower end, a plurality of readily detachable bracing members for maintaining said post in a vertical position, a horizontal boom removably mounted on top of said post for limited swinging movement, one end of said boom projecting over the end of said platform and a readily detachable tension member extending vertically from the other end 20 of said boom to said platform.

5. A loading device having in combination a horizontal platform, a vertical post disposed near one end of said platform, means for maintaining said post in a vertical position, a boom carried at the top of said post for limited swinging movement in a horizontal plane, one end of the boom projecting over the end of the platform nearest said post, a sheave mounted for sliding movement on the projecting end of the boom, means for determining the position of said sheave on the boom, a swinging sheave carried by the other end of the boom, an intermediate sheave carried by said boom, and a cable having one end attached in stationary position to said sliding sheave, the cable being adapted to be connected to a load carrying device and then to pass over said sliding sheave, the intermediate sheave, 40 the swinging sheave, and thence to a power means.

6. A load carrying device having in combination a horizontal platform, a vertical post carried thereby, a boom mounted on top of said post for swinging movement in a horizontal plane, one end of said boom projecting beyond said platform, a member mounted for longitudinal sliding movement on said end of the boom, a transversely swinging sheave mounted on said member and a swinging sheave mounted upon the other end of said boom.

7. A loading device having in combination a portable platform, means for anchoring the same in stationary position, a boom structure carried by said platform, sheaves

on said boom and platform, a load carrier having two sheaves thereon, a locomotive power device, a section of cable connected to said boom running over the sheaves thereon and on the platform and connected to said locomotive power means, and running over sheaves fixedly spaced at separate points at some distance from said device, and over the other sheave on said load carrier whereby backward and forward movement of said power means will move said load carrier to and from the platform.

8. In combination with a loading device, a load carrying member having in combination a frame member having a handle projecting therefrom, an oscillating member journaled in said frame member, a fork secured to and carried by said oscillating member, a bail member having its ends pivotally mounted on the ends of said oscillating member, a tripping device comprising a tongue extending from said fork and a pivoted yoke engaging said tongue carried by said handle, and means for actuating said tripping device to allow the fork to swing with said oscillating member to discharging position.

9. In combination with a loading device, a load carrying member comprising a longitudinal handle member having a bearing in one end, spaced brackets secured to said handle member also having bearings at their ends arranged in alinement with the bearing in the end of said handle, a transverse oscillating member journaled in said bearings, a fork member comprising a plurality of prongs rigidly secured to said oscillating member, a bail extending above and embracing the sides of said fork and having its ends pivotally mounted upon the ends of said oscillating member, a sheave connected to the central part of said bail for swiveling movement thereon, a second sheave mounted for rotation beneath said handle member, a trip device for normally holding the fork in alinement with the handle member, and means for operating said trip device to allow the fork to swing to a discharging position normal to said handle member.

In testimony whereof I affix my signature in presence of two witnesses.

JACOB PLEIN.
